PAINTING ROLLER

Henry A. Schueler, Verona, N. J., assignor to A. G. Jacobus' Sons, Inc., Verona, N. J., a corporation of New Jersey

Application January 13, 1955, Serial No. 481,577

3 Claims. (Cl. 15—230)

This invention relates to painting and decorating, with particular reference to a roller for spreading paint or other coatings, liquid or semi-liquid, or impressing or stippling a design on a flat surface.

The principal object of my invention, generally considered, is to provide painting equipment comprising an improved paint roller applicator for spreading paint evenly over a desired surface.

Another object of my invention is to provide a paint roller device comprising a rod formed with a handle portion, an axle portion disposed at an angle thereto, a roller with a paint absorbent cover, and provided with bearing members rotatively mounted on said axle portion, cap members and a pair of spacer bars extending rigidly from one cap member to the other, the ends of which are respectively secured to each other and to said cap members by said bearing members acting as hollow rivets, each spacer bar having outwardly embossed, longitudinally extending, ribs adapted to press into and bitingly engage the inner surface of the roller cover to hold it firmly in place during use.

A further object of my invention is to provide a paint roller with connecting members extending longitudinally thereof and arranged to firmly engage the internal surface of its cover between its ends, so as to hold it in position.

These and other objects and advantages of the invention will become apparent from the following specification taken with the accompanying drawings. In the drawings wherein like reference characters denote like parts in the several views:

Figure 1 is a side elevational view of a paint roller embodying my invention.

Figure 2 is a transverse sectional view on the line II—II of Figure 1, in the direction of the arrows.

Figure 3 is an elevational view, with parts in axial section, of the roller head comprising end caps and spacer bars which hold the roller cover or hollow cylindrical paint-carrying portion, a fragmentary part of which is shown in axial section.

Figure 4 is a transverse sectional view on the line IV—IV of Figure 1, in the direction of the arrows.

Figure 5 is a fragmentary axial sectional view on the line V—V of Figure 1, in the direction of the arrows.

The present invention involves structural refinements in a paint roller for the application of paint or other coating liquid or semi-liquid and/or for impressing or stippling a design upon a flat surface. The roller device of my invention is so constructed that the head may carry a removable pile roller cover. That is, the cover is easily removed for cleaning or discarding purposes, while during use it is held tight enough so that undesired displacement is avoided. This ease of replaceability, in combination with desirable structural features hereinafter described, are important features of the invention.

Referring to the drawings in detail, like parts being designated by like reference characters, there is shown a roller painter device generally designated 10, and having a combination handle and axle member formed from

2

a desirably steel rod 11. The free end of the handle or hand-adjacent portion of this rod 11 is provided with a desirably wooden handle or hand grip 12, of a shape oval or elliptical in cross-section, as shown in Figure 4, to comfortably fit a user's hand, and from which the rod extends straight a convenient distance. The rod is then shaped or bent at approximately a right angle, providing a straight portion 13. It is then shaped or bent again at a right angle, to form a portion 14, generally parallel to the portion to which the wooden handle directly connects. The rod is then shaped or bent at a right angle, or so as to be generally parallel to the portion 13, to form an axle or journal portion 15. This portion 15 has mounted thereon a paint roller head, generally designated 16. It is also provided with a stop member or portion 17 which may be crimped or otherwise secured to the axle portion 15, to limit movement of the roller to the right, as viewed in Figure 1, as by serving as an abutment for the adjacent bearing member thereof. Movement to the left is limited by the attaching screw 27 threaded into the end of the axle portion 15, as shown in Figure 5.

The paint roller head or frame structure 16 has a paint-dispersing hollow cylindrical cover portion 18, which may be formed of a convenient length and diameter depending upon the area to be painted and the depth of the pile thereon. This cover portion 18 is slidable and tightly held on the roller head 16. It is desirably formed as a core 19, covered by a fabric 21 possessing a pile of dynel, nylon, oran or similar synthetic or natural material which holds a desired amount of paint or other coating material. The depth of this pile may be short or long, depending on the type of coating to be used.

The core 19 of the roller cover is desirably formed of resin-plastic-impregnated heavy paper tubing which will not absorb or be affected by paint, and will not disintegrate, crack, rust or dissolve throughout a normal life. A suitable material is that sold by the Cleveland Container Corporation, Cleveland, Ohio, under the name of "Clevelite" grade EE tubes. However, I do not wish to be limited to the use of this material. The fabric 21 is cut to a desired size and fastened to the core portion in any desired manner, as by means of a suitable adhesive, preferably in a spiral fashion. The spiral winding of the fabric is employed to eliminate undesirable breaks in its continuity.

The roller head 16 comprises a pair of spacer members or bars 22, desirably formed of light metal such as aluminum, .032 inch thick, channelled as illustrated, and provided with longitudinal corrugations 23 intermediate the ends thereof. These corrugations may protrude outwardly from the normal surface of each bar, a distance of about one-sixteenth inch or .062 inch, and be rounded in outline. In the present embodiment I show five of such corrugations on each spacer bar, evenly spaced about 18 degrees. The whole circumferential dimension of each bar may be about 90 degrees, as illustrated. As will be seen from Figure 1, the corrugating of the bars contract them in width slightly between their ends. The ends of said bars are flanged inwardly or bent toward one another, leaving the portions therebetween a convenient length, such as about 6½ inches, overlapped, and connected to end caps 24. These end caps 24, are also desirably formed of aluminum of the same thickness as the bars. They comprise centrally apertured circular end portions, desirably dished inwardly slightly around their apertures, and hollow cylindrical flanges desirably of uniform length around the periphery and extending toward one another. The end flanges of the spacer bars and the end caps are secured together by means of bearing members 25.

These bearing members are each desirably formed of

non-rusting cuprous metal such as bronze or brass, apertured to receive the mounting axle portion 15, headed on the outer end, as indicated at 26 to engage at the one end of the roller the abutment 17, and at the other end the attaching screw 27. The other end of each abutment is upset or riveted over after assembly of the parts, as indicated at 28, to cause said bearing members to function as hollow rivets connecting the end caps 24 to the adjacent flanged ends of the spacer members 22, over which said end caps telescope.

As will be seen in Figure 3, the spacer bars 22 not only have their ends bent at approximately right angles to overlap one another and receive the connecting bearings, but they are off-set slightly inwardly, as indicated at 29, so that they provide indentations receiving the flanges 31 of the caps 24. In other words, the outer surfaces of the flanges 31 are desirably at the same radius from the axis of the roller, as the uncorrugated portions of the spacer bars 22. This means that intermediate portions of said spacer bars lie approximately in the cylindrical plane of the cap side wall portions or flanges and the cover portion 18 may be applied without much friction, even though the fit is fairly close with respect to each end cap 24, until it reaches the corrugations 23 which, as will be seen, decrease in length from the center one toward those on either side thereof.

Upon reaching the corrugations, the interior surface of the core 19 of the roller cover is slightly expanded, or the corrugations sequentially bite thereinto as the roller cover is gradually moved to normal position centered over the head 16. After being positioned, the roller cover 18 is thus tightly held in place by the frictional or biting engagement between the corrugations 23 and the interior surface of the core 19, whereby there is not only during normal or conventional use, no undesired relative turning between the cover 18 and the roller head 16, but there is also no undesired longitudinal movement therebetween. At the same time the fit between the roller cover 18 and the end caps 24 is so close that no appreciable amount of paint, or other coating material, gets inside of the roller during use.

Although I have specified the roller parts, with the exception of the bearings, as being made of aluminum, I do not wish to be limited to this material, as other materials including steel, preferably the stainless variety to avoid rusting, may be employed. The rod 11 although desirably formed of steel, is not limited to this material. If steel is employed it is desirably plated or galvanized, if not of the non-rusting variety.

Having now described this invention in detail in accordance with the requirements of the patent statutes, various changes and modifications will suggest themselves to those skilled in this art, and it is intended that such changes and modifications shall fall within the scope and spirit of the invention, as defined in the following claims.

I claim:

1. A roller device adapted for the application of paint and the like comprising a steel rod shaped to form a handle portion and an axle portion disposed at an angle to said handle portion, a frame structure mounted for rotation on said axle portion, and a cover portion consisting of a fibrous tubular member of an internal diameter corresponding with the external diameter of said frame structure so that it is properly carried thereon, covered with material adapted to hold paint, said frame structure comprising an aluminum cap member adjacent each end of said axle portion, each cap member being formed with a cylindrical side wall of uniform length around its periphery and over which said tubular member is axially slideable, a cuprous bearing for each cap member and journaled on said axle portion, and a pair of channelled aluminum spacer bars, intermediate portions of which lie approximately in the cylindrical plane of the cap side

wall portions, the end portions of which are bent at approximately right angles to the intermediate portions, overlapped with respect to those of the other bar, telescoped in and secured to the cap member by respectively receiving the bearing of each cap member in appropriate apertures, which bearings are riveted over the assembled parts for holding them together, each of the spacer bars being formed with a series of longitudinal outwardly-projecting corrugations decreasing in length from a central one toward those at the sides, the ends of each corrugation being tapered to gradually merge into the uncorrugated portions of said bars, whereby on assembly of the tubular member with the frame structure, the corrugations gradually bite into the inner fibrous surface thereof and positively prevent slippage during normal use.

2. A roller device adapted for the application of paint and the like, comprising a rod in angular form and providing a handle portion and an axle portion, a roller frame structure mounted for rotation on said axle portion, said structure consisting of a cap member adjacent each end of said axle portion with a cylindrical side wall of uniform length around its periphery and adapted to snugly telescope within a tubular member, covered with material adapted to hold paint, a bearing for each cap member journaled on said axle portion, and a pair of spacer bars intermediate portions of which lie approximately in the cylindrical plane of the cap side wall portions, the end portions of which are bent at approximately right angles to the intermediate portions, overlapped with respect to those of the other bar, telescoped in and secured to the cap members by respectively receiving the bearing of each cap member in appropriate apertures, which bearings are shaped so that they function as hollow rivets for holding the parts assembled, each of the spacer bars being formed with a series of longitudinal outwardly-projecting corrugations decreasing in length from a central one toward those at the sides, the ends of each corrugation being tapered to gradually merge into the uncorrugated portions of said bars.

3. A roller device adapted for the application of paint and the like, comprising a rod shaped to form a handle portion and an axle portion, a roller frame structure mounted for rotation on said axle portion, said structure consisting of a cap member adjacent each end of said axle portion formed with a cylindrical side wall of uniform length around its periphery and projecting toward the other cap member, a bearing for each cap member journaled on said axle portion, and a pair of spacer bars, intermediate portions of which lie approximately in the cylindrical plane of the cap side wall portions, the end portions of which are bent at approximately right angles to the intermediate portions, overlapped with respect to those of the other bar, telescoped in and secured to the cap members by respectively receiving the bearing of each cap member in appropriate apertures, said bearings being shaped so that they function as hollow rivets for holding the parts assembled, the spacer bar parts between the intermediate and end portions thereof being inset to a diameter corresponding with the inner diameter of the cap side walls, snugly receiving the same, leaving shoulders at the junctions with said intermediate portions closely approached by the inner edges of the cap side walls, so as to provide a substantially continuous cylindrical surface of uniform diameter from the outer ends of said caps to the intermediate portions of said spacer bars for snugly fitting in a tubular member adapted to hold paint on its outer surface.
